(57) **CLAIM**

We claim the ornamental design for a light-emitting diode bulb, as shown and described.

DESCRIPTION

FIG. 1 is a perspective view of a light-emitting diode bulb showing our new design;

FIG. 2 is another perspective view thereof;

FIG. 3 is a cross-section perspective view thereof, shown with an upper round portion removed, taken along line 3-3 of FIG. 5;

FIG. 4 is another cross-section perspective view thereof, shown with an upper round portion removed;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top plan view thereof; and,

FIG. 10 is a bottom plan view thereof.

The broken lines are directed to unclaimed features. The broken lines form no part of the claimed design.

1 Claim, 9 Drawing Sheets
